(57) **CLAIM**

The ornamental design for a bath mirror, as shown and described.

DESCRIPTION

FIG. 1 is a front, right and top perspective view of a bath mirror, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 2.

FIG. 10 is a cross-sectional view of the bath mirror of FIG. 1, taken along section line 10-10 as depicted in FIG. 3; and, FIG. 11 is a partial enlarged view of an area labeled 11 in FIG. 10.

The broken lines shown in the drawings are included for the purpose of illustrating portions of the bath mirror that form no part of the claimed design. In addition, the dot-dash lines in FIGS. 2 and 9-11 illustrate enlarged portions of the claimed design.
